UNITED STATES PATENT OFFICE.

IVAN TREPANIER, OF WATERBURY, CONNECTICUT.

COMBINATION LOCK.

Application filed January 19, 1927. Serial No. 162,093.

This invention relates to what is commonly known in the art as a combination lock; that is, a device which includes, among other parts, knob actuated disks and a graduated indicating dial for showing the relative positions of the disks.

The present improvement is directed to a casing wherein a plurality of superposed disks are arranged for independent rotation, these being provided with notches adapted to be brought into registry with each other by proper manipulation of an operating shaft, the disks serving to control a novel latch structure which functions as coupling and retaining means between the casing and a special keeper plate.

The specific construction of the details together with their relative arrangement, producing the alleged novelty, will become apparent from the following description and drawings.

In the accompanying drawings forming a part of this application, and in which like numerals are employed to designate like parts throughout the same:—

Figure 1 is a view in side elevation, showing the cover plate of the casing removed,

Fig. 2 is a horizontal section through the same,

Fig. 3 is a perspective view of a prominent detail,

Fig. 4 is a top plan view of one of the locking disks,

Fig. 5 is a perspective view of the knob operated shaft.

Referring to the drawings in detail, it will be seen that the reference character 1 designates a casing of suitable configuration open on one side and of a depth to accommodate the tumbler disks structure 2. A cover plate 3 is disposed over said open side and held in place by retaining bolts 4. The reference character 5 designates a face plate disposed against one side of the support 6 and held in place by the bolts 4.

At this time, I would direct attention to the fact that the disk structure 2 includes four separate disks 7, three of which are represented by the reference character 7, and one by the reference character 7^a. The disks 7 are provided with depressions 8 on one side and an extension 9 on the opposite side together with an intervening notch 10. (See Fig. 4.) These disks 7 are mounted for free rotation upon a bushing which is

in turn mounted upon an operating shaft 11. The disk 7^a is fastened rigidly to the shaft however, and is provided with an appropriate cam as shown in Fig. 1. The shaft 11 is bifurcated at one end as at 12 and extends through an opening in the support 6 and beyond this opening, and a knob 13 is fitted thereon and provided with a cross pin 14 extending through and beyond the bifurcations.

The disks 7 and 7^a cooperate in a customary manner upon rotation of the shaft so that when rotating the shaft in a predetermined manner, the notches on the several disks 7 may be brought into registry. In this connection, attention is invited to an indicating dial 15 which cooperates with the knob to indicate the approximate condition of the concealed disks on the interior of the casing.

Obviously, by rotating the shaft in one direction for a predetermined distance, the cooperating pins 9 on the disks will successively come into play for picking up the disks in proper order to bring the notches into registry. Incidentally, the depressions 8 have no function in the operation of the tumblers, this being merely one way of forming the extension pins 9. Attention is now invited to Fig. 3, wherein it will be seen that the reference character 16 designates generally a latch and operating means therefor. The latch itself is designated by the reference character 17 and comprises a flat metal strip 18 having one end directed upwardly as at 19 and terminating in a horizontal extremity 19.

A right angular part 20 on the opposite end serves to provide somewhat the same sort of a retainer. These retainers 19 and 20 are adapted to extend through openings in guide brackets 21 on the interior of the casing, and also through openings in ears 22 carried by a keeper plate 23. It will be noticed that the retainer 20 is formed by striking the metal upwardly and this provides a pair of furcations 24 and 25 having downturned extremities straddling and engaging the upper end of a pivotally mounted actuator 26. The latter is provided at its lower end with spaced parallel ears 27 pivotally connected in the casing in the manner shown.

A flat spring 28 is mounted in the casing and cooperates with these ears in a manner to exert pressure upon the actuator to swing

it in a direction toward the tumbler disks. The intermediate portion of the actuator is provided with a bracket 29 of right angular form which is mounted to permit one flange 6 thereof to move into the registered notches 10.

In practice, the knob 13 is operated in a customary manner to also operate the dial 15 and the spindle or shaft 11. This will 10 operate the tumblers in a successive and well known manner in order to bring the notches 10 into registry upon proper manipulation of the tumblers as indicated by the dial. I would direct attention to the fact that the 15 pin and slot connection between the knob and the spindle is such as to allow the knob to move outwardly and yet maintain a rotating connection with the spindle in case of an increased thickness in the mounting member 20 6.

Obviously, when the notches are in alignment or registry, this allows the bracket 29 to snap into the same, and in so doing, it serves to exert an endwise thrust upon the 25 latch 17 to disengage the retainers 19 and 20 from the keepers 22.

It is believed that by considering the de-

scription in connection with the drawings, a clear understanding of the invention will be had. Therefore, a more lengthy description 30 is thought unnecessary.

Having thus described my invention, what I claim as new is:—

In a structure of the class described, a hollow casing, a spindle mounted for rotation in said casing, tumbler disks carried by said spindle, said disks being provided with notches adapted to be brought into registry, and with cooperating means for operating them in succession and under predetermined conditions, a pivotally mounted actuator in said casing provided with a bracket adapted to be received in said notches when in registry, a latch disposed at right angles to said actuator, said latch having one end bifurcated, and the furcations being formed to engage the upper end of said actuator, said latch being also provided with a pair of retainers, and apertured brackets in said casing with which said retainers are adapted to slidably coat.

In testimony whereof I affix my signature.

IVAN TREPANIER.
